TION OF OHIO.

CARD-INDEX TAB.

Application filed February 16, 1922. Serial No. 537,018.

To all whom it may concern:

Be it known that we, HAROLD C. McPIKE and FRED A. SCHMITZ, citizens of the United States, residing at Youngstown, in the county of Mahoning and State of Ohio, have invented certain new and useful Improvements in Card-Index Tabs, of which the following is a specification.

This invention relates to an improvement 10 in index tabs for guide cards of filing systems.

A primary object of the invention is to provide a strong and durable tab construction which will more readily withstand the 15 bending stresses usually placed upon the tab in fingering over the guide cards to locate the desired section or sub-division. As the index tab projects above the upper edge of the card while the card itself is 20 more or less firmly anchored between the contents of the filing drawer, the tab forms a cantilever, and if not substantially constructed and designed, breaks or cracks at the fulcrum point where all of the strain 25 is focused.

Accordingly, the present invention contemplates a novel tab having a compartment for receiving the label, the walls of said compartment being transparent and 30 provided with an opening for inserting and removing the label, the said opening being arranged and disposed in such a way that the structure of the tab is in no way weakened in the zone where the bending or levering 35 age strains are concentrated.

A further and more specific object of the invention is to provide a simple, sanitary, and practical construction that may be easily and economically manufactured.

With the above and other objects in view which will more readily appear as the nature of the invention is better understood, the same consists in the novel construction, combination, and arrangement of parts, 45 hereinafter more fully described, illustrated and claimed.

A preferred and practical embodiment of the invention is shown in the accompanying drawings, in which:

Figure 1 is a front elevation of a portion 50 of a guide card having the improved tab applied thereto.

Figure 2 is a rear view of the guide card and tab construction shown in Figure 1.

Figure 3 is a vertical sectional view taken 55 on the line 3—3 of Figure 1.

Figure 4 is a horizontal sectional view taken on the line 4—4 of Figure 1.

Figure 5 is a rear elevation of a guide card showing a modified type of tab construction providing two access openings for the label compartment.

Similar reference characters designate corresponding parts throughout the several figures of the drawings.

According to the present invention, it is proposed to provide the guide card 1 with an integral tab projection 2 projecting above the upper edge 3 of the guide card a suitable distance to enable the tab to be readily sighted and distinguished when the guide card is in position in the filing drawer. The tab projection 2 is preferably cut away or punched out, as indicated at 4, thereby providing an opening whose lower edge 50 extends well into the body of the guide card so as to carry the relatively weakest point of the tab to a point below the upper edge thereof and enable the material of the card to better resist the bending strain 55 which is concentrated more or less at this otherwise weak point of the tab.

The recess or opening 4, as well as the opposite faces of the tab, are covered by an enveloping sheet 5 of transparent material, preferably celluloid, the same being folded over the edge of the tab so as to present a continuous and smooth protecting edge 6 for the top of the tab to prevent the same from becoming soiled or curled up by fingering and also prevent the celluloid from being separated from the body of the tab. In other words, the celluloid sheet 5 is folded upon itself and placed astride the tab so that its folded edge is located at the top of the tab while the opposite wings thereof provide transparent walls *w* and *w'* for the recess 4 thereby providing a compartment for receiving and holding a label *L* bearing the necessary indicia for identifying the contents of the file drawer.

By reason of the fact that the recess 4 extends above and below the upper edge 3 of the card body 1, a label within the compartment may contain upper and lower lines of indexing matter such for example as a relatively large general index letter which may be on the upper half of the label and always

exposed to view while the portion of the label below the upper edge of the card may contain further and more explicit data as to the contents of the particular subdivision.

5 As previously indicated the novel and distinctive feature of the present invention is to provide a tab construction which is reinforced where the bending pressure is usually centered and to that end the access 10 opening for the label compartment is especially arranged with reference to the focusing point of such strains. That is to say, the slit opening 7 which permits access to the label compartment is vertically arranged at 15 an end of the compartment and parallel with one of the vertical edges of the recess 4 instead of horizontally, that is parallel with a horizontal edge of the opening. By thus locating the access slot or opening 7 at right 20 angles to the fulcruming line of the cantilever a minimum area only of the celluloid is required to be cut away or removed, while at the same time the full reinforcing effect imparted to the material of the tab by the 25 celluloid wings *w* and *w'* of the sheath 5 is not disturbed. Therefore, the tab remains fully reinforced by the stiffness of the protecting sheath or cover, enabling it to successfully withstand bending strains which 30 would otherwise be focused at the horizontal or longer edge of the recess 4 and in the relatively small web portions 2^a of the tab.

While it will of course be understood that 35 the distinguishing characteristic of the present improvement resides in the particular disposition of the access slot or opening 7, it will of course be understood that the invention is not limited to the use of a single 40 opening adjacent one of the vertical edges

of the recess of the tab, but as shown in Figure 5 the rear wing of the transparent reinforcing sheath 5 may be provided with slits 7^a and 7^b located at opposite ends of the recess and parallel to the vertical edges 45 thereof leaving the area of material in the card and sheath at the point where the hinging action is focused substantially undisturbed and thereby materially contributing to the strength and durability of the entire 50 construction.

Without further description it is thought that the features and advantages of the present improvement will be apparent to those skilled in the art and it will of course be understood that changes in the form, proportion and minor details of construction may be resorted to without departing from the spirit of the invention or scope of the appended claim.

60 We claim:—

A tab for guide cars including a card body having a tab extension provided with a recess lying within the extension and also extending into the card body, a sheath of transparent material folded to embrace the tab projection so that the wings thereof cover opposite sides of the recess to provide a label-receiving compartment, and a vertical slot in one of the wings of the sheath located adjacent one of the vertical edges of the recess.

65 In testimony whereof we hereunto affix our signatures in the presence of two witnesses.

HAROLD CURTIS McPIKE.
FRED A. SCHMITZ.
